his ATTORNEY

UNITED STATES PATENT OFFICE.

ERNST KOERTING, OF PEGLI, ITALY, ASSIGNOR TO SCHUTTE & KOERTING COMPANY, OF PHILADELPHIA, PENNSYLVANIA, A CORPORATION OF PENNSYLVANIA.

INJECTOR.

1,111,541.

Specification of Letters Patent. Patented Sept. 22, 1914.

Application filed January 16, 1914. Serial No. 812,397.

To all whom it may concern:

Be it known that I, ERNST KOERTING, a subject of the Emperor of Germany, residing in Pegli, in the Province of Liguria, in the

5 Kingdom of Italy, have invented certain new and useful Improvements in Injectors, of which the following is a true and exact description, reference being had to the accompanying drawings, which form a part 10 thereof.

My invention relates to boiler feed injectors and has for its object to provide a device especially adapted for economically feeding hot water to a boiler.

15 In another application filed February 19, 1914, Serial Number 819,606, I have shown and described a device having similar purposes and in which I combine with a, preferably double tube, injector a jet pump to 20 raise the pressure of the feed water and a feed water heater through which the water is forced by the jet pump and fed to the injector at a high temperature and sufficient pressure to enable the injector to handle it.

25 My present invention consists broadly in the use of a jet pump having perforations formed in its combining tube and a steam chamber (preferably for exhaust steam) surrounding said perforated combining tube in 30 combination with an injector tube or tubes to which the heated water from the jet pump is forced under sufficient pressure to enable the injector to work.

The details of my invention will best be 35 understood as described in connection with the drawing which shows in section an injector casing constructed and equipped to embody my invention in what I consider to be its best form and in which A is the casing 40 having a steam inlet B opening into a chamber B' from which lead the nozzles C, C', C'', supplying steam to the three combining tubes of the apparatus.

D, D', D'' are valves controlling the admission of steam to the nozzles and actuated 45 as shown by a hand lever D⁶ acting through spindle D⁸ and cross bar D⁴ on the valves.

E is the admission port for feed water.

F, F', F'' are the combining tubes of the 50 jet pump and injectors. The portion F'' of the pump tube is formed with perforations

leading through it and is surrounded by a chamber H' having a connection H by which it can be connected to a supply of exhaust steam.

55

G, G', G'' are chambers in casing A connecting the tubes F, F', F'' in series, the chamber G'' connecting through port L and valve M with the boiler.

N is an overflow valve casing connecting 60 with chambers G, G', G'' through ports O, O' and O'' and connecting at bottom to chamber N' and overflow port N''.

P is a valve rod carrying valve P' which in turn carries valve P''.

65

The overflow valve is preferably connected to be operated by lever D⁶, such connection being indicated, Q being an eccentric, Q' a connecting rod, Q'' an eccentric and Q³ a yoke connecting to rod P, but as all the 70 mechanism for actuating the overflow valve is old and well known I have not illustrated it in detail and will not further refer to it.

It will be obvious that when steam is admitted to the three combining tubes the pressure of the feed water will be raised progressively in the second and third tubes and when steam, (preferably exhaust steam), is admitted to chamber H' it will be sucked into the combining tube of the jet pump F 80 and raise the temperature of the feed water delivered to the chamber G and the tubes F' and F''.

75

By my construction I am enabled to economically heat and deliver to a boiler 85 feed water and while my invention is of general utility it is particularly useful for use in connection with locomotive boilers.

Having now described my invention, what I claim as new and desire to secure by Letters Patent is:

90

1. A boiler feeding device for feeding hot water consisting of a jet pump having perforations formed in its combining tube and a steam chamber inclosing said combining tube in combination with an injector connected to receive the heated water delivered by the jet pump.

95

2. A boiler feeding device for feeding hot water consisting of a jet pump having perforations formed in its combining tube and a steam chamber inclosing said combining tube 100

in combination with a two tube injector connected to receive the heated water delivered by the jet pump.

3. A boiler feeding device for feeding hot water consisting of a casing chambered to receive three combining tubes set in series and having a separate chamber inclosing the first combining tube and a valved chamber

for the live steam with jets leading to each tube in combination with three combining tubes, the first of which is perforated to communicate with the chamber inclosing it.

ERNST KOERTING.
